ENCLOSED CIRCUIT BREAKER

Delbert Ellis, Forest Hills, Pa., assignor to Westinghouse Electric & Manufacturing Company, East Pittsburgh, Pa., a corporation of Pennsylvania

Application June 17, 1938, Serial No. 214,206

28 Claims. (Cl. 200—50)

The invention relates generally to enclosed electrical switches or circuit breakers and more particularly to devices for operating circuit breakers which are enclosed in cabinets.

An object of the invention is the provision of an improved operating device for operating a circuit breaker which is enclosed in a cabinet.

Another object of the invention is the provision of an operating device for operating a circuit breaker enclosed in a cabinet, in which the operating device is so constructed that it insures against breakage of the breaker handle when the cover of the cabinet is slammed shut.

Another object of the invention is the provision of an operating device for operating a circuit breaker enclosed in a cabinet, which will prevent breakage of the breaker handle when the cover of the cabinet is slammed shut even though the operating handle on the cover and the breaker handle in the cabinet are widely displaced relative to one another when the cover is slammed shut.

Another object of the invention is the provision of a cabinet having an openable cover and an operating handle thereon for operating a circuit breaker disposed within the cabinet, in which means is provided for automatically establishing an operative connection between the operating handle and the breaker handle when the cover is closed even though the operating handle and the breaker handle are displaced relative to one another during closing of the cover.

Another object of the invention is the provision of means for preventing accidental movement of the handle of a circuit breaker to closed position when the cover of the cabinet which encloses the breaker unit is open.

Another object of the invention is the provision of means for locking the cover of the cabinet closed in all positions of the operating handle except when the handle is moved to an "open cover" position beyond the "off" position, which means also prevents accidental movement of the handle of the circuit breaker to the "on" position when the cover of the cabinet enclosing the breaker is open.

Another object of the invention is the provision of an interlocking mechanism for the cover of a circuit breaker cabinet which may be released by movement of an operating handle on the cover to a predetermined position, and which also serves to prevent accidental movement of the handle of the circuit breaker to the "on" position when the cover is open.

The novel features that are considered char- 55

acteristic of the invention are set forth in particular in the appended claims. The invention itself, however, both as to structure and operation, together with additional objects and advantages thereof will be best understood from the following detailed description of a preferred embodiment thereof when read in conjunction with the accompanying drawings, in which:

Fig. 1 is a plan view of a cabinet and operating device for a circuit breaker, constructed in accordance with the invention, the breaker and operating handle being shown in the "on" position;

Fig. 2 is a plan view of the cabinet with the cover removed to show a portion of the operating means for operating the breaker handle;

Fig. 3 is a plan view of the cabinet similar to Fig. 1, but showing the operating handle in the "reset-open cover" position;

Fig. 4 is a longitudinal sectional view of the cabinet showing the breaker unit and the operating device in elevation, the operating handle being in the "off" position;

Fig. 5 is a transverse sectional view of the cabinet taken on the line V—V of Fig. 3, the operating handle being shown in the "reset open cover" position;

Fig. 6 is a fragmentary sectional view of the cover taken substantially through the center line of the operating handle;

Fig. 7 is a perspective view of the movable locking element for locking the cover in closed position;

Fig. 8 is another perspective view of the movable locking element taken from the opposite direction from that of Fig. 7;

Fig. 9 is a perspective view of the operating member for moving the breaker handle; and,

Fig. 10 is a fragmentary view of the interlocking means for the cover.

Referring to the drawings, the enclosing cabinet shown comprises a rectangular box-like metal casing 15, and a cooperating metal cover or door 17. The cover 17 is provided with a rim 19 which seats against the edges of the side and end walls of the casing, and has a downwardly extending edge 21 which overlaps the edges of the casing 15. The cover 17 is secured to one of the walls of the casing 15 by means of a pair of hinges 23 which permit the cover to be swung to open and to closed positions. A felt pad 25 (Figs. 4 and 5) is interposed between the rim 19 and the edges of the casing 15 to exclude dust and dirt from the interior of the cabinet, which is designed to house and protect electrical

switches and circuit breakers for industrial applications where the air may contain large amounts of dust and dirt.

In the embodiment of the invention illustrated, a circuit breaker unit 27 having an oscillatable operating handle 28 for operating the breaker mechanism is enclosed by the cabinet and mounted on brackets 29, which are secured to the back wall 31 of the casing 15. The circuit breaker unit 27 is preferably of the type fully described in Patent 2,047,739, issued to H. J. Lingal July 14, 1936, and assigned to the assignee of the present invention.

The circuit breaker 27, which is fully described in the above-mentioned patent, has at least one pair of separable contacts 35 and 37 (Fig. 4), and an operating mechanism (not shown) for opening and closing the contacts by movement of the handle 28 to "off" and "on" positions. The breaker mechanism has a releasable trigger or cradle member 39 which when released causes the mechanism to effect opening of the contacts and also causes movement of the breaker handle 28 to a tripped position intermediate the "on" and "off" positions. A latch 41 normally restrains the cradle member 39 in operative or set position, as shown in Fig. 4. A current responsive trip device indicated generally at 43 is operable in response to predetermined overload conditions to effect release of the latch 41 and the cradle member 39 to effect opening of the contacts of the breaker.

In order to reclose the contacts following an automatic tripping operation by the current responsive trip device, it is necessary to first reset the mechanism by moving the handle 28 to a "reset" position beyond the "off" position. This movement of the handle 28 to the "reset" position returns the cradle member 39 to latched position where it is reengaged and held by the latch 41. The breaker mechanism and trip device are fully described in the above-mentioned patent, to which reference may be made for details of construction and operation of the circuit breaker.

While a particular type of circuit breaker has been briefly described and referred to, any suitable circuit breaker or switch unit having an oscillatable operating handle may be mounted in the casing 15.

An operating handle 45 is rotatably mounted on the exterior surface of the cover 17 and is secured to a stub shaft 47 which extends through a bushing 49 provided in the cover 17. An actuating member comprising a cross-pin 51 is secured to the inner end of the stub shaft 47 by being tightly fitted in a transverse opening provided therefor in the lower end of the stub shaft 47. The cross-pin 51 and the stub shaft 47 form a part of a means for operatively connecting the operating handle 45 to the breaker handle 28 when the cover 17 of the cabinet is closed, as will hereinafter appear.

An operating member 53 is rotatably mounted on a shouldered pivot stud 55 (Fig. 2) which is secured to a rigid supporting plate 57 in the casing 15. The operating member 53 (Fig. 9) comprises a U-shaped metal plate having longitudinally extending legs or side walls 59 joined by an integral base or bight portion 61. The base portion 61 of the operating member 53 is provided with a centrally disposed opening which engages the pivot stud 55. A cap screw 63 (Fig. 2) is threaded in the end of the pivot stud 55 to retain the operating member 53 in mounted position on the stud.

The supporting plate 57 is mounted on the top of the circuit breaker unit 27 and is rigidly secured thereto and to the brackets 29 by means of a plurality of bolts 65, which extend through the casing of the breaker unit and engage the brackets 29. A plurality of screws 66 are also provided for securing the supporting plate 57 to the cover of the circuit breaker unit 27. The pivot stud 55, which is rigidly secured to the supporting plate 57, is disposed in alignment with the axis of the stub shaft 47 so that the operating handle 45 and the operating member 53 are both rotatable about the same common axis when the cover 17 is in closed position.

A clevis spring 67 is mounted on the operating member 53 by having its arms 69 clinched in openings provided therefor in the lower edges of the longitudinally extending legs 59 of the operating member 53 on opposite sides of the pivot axis of the operating member, as best shown in Figs. 2 and 4. The arms 69 of the clevis spring 67 extend laterally from the operating member 53 and are bent inwardly toward one another to engage the opposite sides of the breaker handle 28. The arms 69 of the clevis spring have sufficient stiffness to move the breaker handle 28 when the operating member 53 is rotated in either direction, and yet are sufficiently resilient to deflect and prevent breakage of the breaker handle 28 when abnormally large forces are applied to the operating handle 45 and operating member 53. Rotation of the operating member 53 in either direction is limited by the engagement of the left-hand ends 70 of the two side walls 59 of the member with a projection 72 on the supporting plate 57.

In order to automatically effect an operative connection between the operating handle 45 and the operating member 53 when the cover 17 is closed, the side walls or legs 59 of the operating member 53 are provided with a pair of aligned V-shaped notches 71 disposed on opposite sides of the pivot axis of the operating member for receiving the ends of the cross-pin 51, which is connected to the operating handle. The lower portions of the notches 71 are of slightly greater width than the diameter of the cross-pin 51, and the edges of each notch slope away from each other, as indicated at 73, and terminate in the upper edge of the sidewall 59. The sloping edges 73 of the notches serve to guide or cam the cross-pin 51 into the lower ends of the notches 71 and cause the operating handle 45 to assume a position corresponding to that of the operating member 53 and breaker handle 28 when the cover is closed, irrespective of the position which the operating member 53 and breaker handle 28 may occupy during closing of the cover. The cross-pin 51 is thus caused to move into the lower portions of the V-shaped notches 71 of the operating member 53 to establish an operative connection between the operating handle 45 and the breaker handle 28 when the cover is closed.

The height of the side walls 59 and the slope of the edges of the V-shaped notches 71 may be made such as to cause movement of the operating handle 45 to a position corresponding to that of the operating member 53 and to effect an operative connection between the operating handle 45 and the operating member 53 when the cover is closed, even when the operating handle 45 and the operating member 53 are in extreme opposite positions during closing of the cover as, for example, when the operating handle is in the "on" position and the operating member and

breaker handle are in the "off" position. However, this would necessitate increasing the height of the side walls 59 of the operating member 53 and consequently the height of the cabinet.

In order to obviate the necessity of increasing the height of the operating member and cabinet, a spring means, which will hereinafter be described, is provided for biasing the operating handle to a central position intermediate the "on" and "off" positions when the cover is open. Since the spring means biases the operating handle to a central position when the cover is open, the height of the operating member 53 and the slope of the edges of the V-shaped notches 71 need only be sufficient to cause the operating handle 45 to move from its central position to either the "on" or "off" positions, depending upon the position the breaker handle occupies when the cover is closed, to effect an operative connection between the operating handle and the breaker handle.

The exterior surface of the cover 17 is marked with suitable indicia, such as "On," "Tripped," "Off," "Reset," and "Open cover" to indicate the various positions of the handle 28 of the circuit breaker. The movement of the operating handle 45 in either direction is transmitted through the stub shaft 47 and the cross-pin 51 to the operating member 53 to cause corresponding movement of the operating member and consequently the breaker handle 28. The circuit breaker is closed by moving the operating handle 45 in a counter-clockwise direction to the "on" position, and opened by movement of the operating handle in the opposite direction to the "off" position. The mechanism of the circuit breaker, including the cradle member 39, may be reset following an automatic trip operation by moving the operating handle 45 to the "reset" position, which is beyond the "off" position in the opening direction. The movement of the operating handle 45 to the "open cover" position, which is beyond the "reset" position, effects release of a cover locking means to permit opening of the cover 17, as will be hereinafter described.

The provision of the operating member 53 and its mounting on the rigid supporting plate 57 prevents breakage of the breaker handle 28 when the cover is slammed shut. This results from the fact that the forces produced by slamming of the cover are taken by the operating member 53 and the supporting plate 57, and are not transmitted to the breaker handle.

An interlocking means indicated generally at 75 is provided for normally locking the cover 17 to prevent opening thereof. The interlocking means 75 is effective to lock the cover in all positions of the operating handle 45 except when the handle is moved to the "open cover" position. The locking means comprises a locking element or catch 77, which is secured to the under side of the cover 17, and a movable U-shaped locking element 79, which is pivotally mounted on the supporting plate 57. The locking element 77 is secured to the cover 17 by means of a pair of rivets 81 (Fig. 5) and has a V-shaped hook portion 83, the end of which is adapted to hook under and engage the bight portion of the U-shaped movable locking element 79 (Figs. 7 and 8) when the movable locking element is in a vertical cover locking position. The U-shaped locking element is pivotally mounted on the supporting plate 57 by means of a pivot pin 85 which is carried by a pair of projections 87 struck up

from the supporting plate 57. The pin 85 extends through the projections 87 and through openings provided therefor in the lower ends of the legs 89 of the locking element 79.

5 The U-shaped locking element 79 is biased in a counter-clockwise direction, as viewed in Fig. 5, to a handle locking position beyond the vertical cover locking position by means of a coil spring 91 which encircles the pivot pin 85. One of the legs 89 of the locking element 79 has a projection 93 which is adapted to engage the supporting plate 57 to limit clockwise movement of the locking element when the cover is open. The bight portion of the locking element 79 has a downwardly extending projection 97 which is adapted to engage the hooked end 83 of the locking element 77 when the cover 17 is closed. The projection 97 limits clockwise movement of the locking element 79, as viewed in Fig. 5, when the cover is closed, so as to cause the locking element to assume a substantially vertical cover locking position.

25 The side walls 59 of the operating member 53 are provided with extending arms 99 and 101 which project longitudinally from the upper right-hand corners of the side walls. The arm 101 of the operating member 53 is adapted to engage one of the legs 89 of the locking element 79 to move the locking element to released position when the operating handle 45 is moved to the "open cover" position, as shown in Figs. 3 and 5, to permit opening of the cover 17. The locking element 79 is moved to released position by the operating member 53 only when the operating handle 45 is moved to the "open cover" position, and is effective to lock the cover 17 closed in all other operating positions of the operating handle 45.

30 To open the cover 17, it is necessary to move 40 the operating handle 45 to the "open cover" position. When the operating handle is thus moved to the "open cover" position, the arm 101 of the operating member engages and moves the locking element 79 in a counter-clockwise direction, as viewed in Fig. 5, to a released position, in which the bight portion thereof is clear of the hooked end 83 of the locking element 77. The cover 17 is now released and may be swung to open position. When the cover 17 is opened, the 45 cross-pin 51 separates from the operating member 53, and the operating member and breaker handle 28 are returned to the "off" position by an overcenter spring of the breaker operating mechanism. This movement of the operating member 53 to the "off" position permits the locking element 79 to be moved in a clockwise direction, as viewed in Fig. 5, to a handle locking position in which the projection 93 thereof engages the supporting plate 57.

50 The interlocking means 75, in addition to preventing opening of the cover, also serves to prevent accidental movement of the breaker handle 28 to the "on" position when the cover 17 is open. For this purpose, one of the legs 89 of the locking element 79 is provided with an offset lateral projection 103, which projects into the path of movement of the leg 99 of the operating member 53 when the cover is opened, and the locking element is in its handle locking position beyond its vertical position, with its projection 93 engaging the plate 57. Since the projection 103 extends into the path of movement of the arm 99 when the cover is open, the handle 28 of the breaker cannot be moved in a closing direction toward the 55 "on" position a sufficient distance to cause the

breaker mechanism to close the contacts of the breaker. However, an authorized person having knowledge of the operation of the interlocking means 75 may move the breaker handle 28 to the "on" position when the cover is open by manually moving the locking element 79 in a counter-clockwise direction, as viewed in Fig. 5, either to the vertical position or released position. This movement of the locking element 79 causes the lateral projection 103 thereof to be moved downwardly out of the path of movement of the arm 99 of the operating member 53, so that the operating member 53 and breaker handle 28 may be moved to the "on" position. The offset projection 103 is maintained below and out of the path of the arm 99 of the operating member 53 when the cover is closed by reason of the fact that the hooked end 83 of the locking element 77 engages the depending projection 97 of the locking element 79 to maintain the locking element in the vertical cover locking position.

When the cover is moved to closed position, the hooked end 83 of the locking element 77 forces the movable locking element 79 back to clear the same, and when the cover reaches closed position, the biasing spring 91 returns the locking element 79 to the vertical cover locking position.

The offset projection 103 of the locking element 79 is provided with a recess 105 for receiving a padlock to positively prevent movement of the breaker to the "on" position when the cover is open. The bow of the padlock is inserted in the recess 105 between the edge of the recess and the plate 51, and when in this position the padlock prevents movement of the locking element 79 away from its handle locking position.

The operating handle 45 is channel-shaped in section and is provided with a hub portion 107. The central portion of the hub is depressed, as shown in Fig. 6, to provide a rim 109 of inverted U-section which forms a downwardly facing circular channel. The hub 107 and its rim 109 form a part of a locking means for locking the operating handle in the "off" position. The handle locking means has been fully described and is claimed in the copending application of Gilbert Currie, Serial No. 212,874, filed June 10, 1938, and assigned to the assignee of this invention. This means for locking the operating handle in the "off" position comprises a plurality of spaced apertures 111 which are formed in the rim 109 of the handle 45 for receiving a plurality of padlocks. A cup-shaped locking element 113 is rotatably mounted on the stub shaft 47 beneath the hub portion 107 of the operating handle 45, and this element has a circular flange 115 which projects into the circular channel formed by the rim 109 of the operating handle 45. The circular flange 115 of the cup-shaped locking element 113 is provided with a plurality of spaced apertures 117 which are adapted to align with the apertures 111 in the handle 45 when the handle is moved to the "off" position.

A lever 119 is pivotally mounted on a pin 121 projecting from the exterior surface of the cover 17, and this lever has an enlarged rounded end 123 which is engaged between the side edges of the operating handle 45, as shown in Figs. 1 and 3. The opposite end of the lever 119 carries a pin 125 (Fig. 6) which engages an arcuate slot 126 formed in the base and flange of the locking element 113.

When the operating handle 45 is in the "off" position, the apertures 117 in the cup-shaped locking element 113 register with the apertures 75

111 formed in the hub of the operating handle 45 so that a plurality of padlocks may be inserted or hung in the apertures. The insertion of even a single padlock in a pair of the apertures 111 and 117 is effective to lock the operating handle in the "off" position, so as to prevent movement thereof in either direction away from the "off" position. When the operating handle is thus locked in the "off" position, it cannot be moved away from that position until all of the padlocks have been removed.

When the operating handle 45 is moved away from the "off" position, it carries with it the large end 123 of the lever 119 to cause the cup-shaped locking element 113 to be rotated in an opposite direction from that of the operating handle, so that a very small movement of the operating handle will effect closing of the apertures through which the padlocks are inserted, thus making it impossible to insert the padlocks in any other position of the operating handle 45 except the "off" position. The end of the lever 119 which carries the pin 125 is adapted to engage the side edges of the operating handle 45 to limit rotation of the handle 45 in either direction to limits corresponding to the limits of rotation of the operating member 53, as shown in Figs. 1 and 3.

A coil spring 127 is provided for biasing the operating handle to a central position intermediate the "on" and "off" positions thereof. The spring 127 has one of its ends connected to the enlarged rounded end 123 of the lever 119 and its other end connected to the end of the operating handle 45. When the operating handle 45 is on either side of its central or intermediate position, the spring 127 is tensioned, and when the handle 45 is released and the cover is open, the spring 127 automatically returns the operating handle to the central or intermediate position. The spring 127, by biasing the operating handle to the central position, insures that the cross-pin 51 will be in a position to engage the slanting edges 73 of the V-shaped notches 71 of the operating member 53, irrespective of the position which the operating member and breaker handle may occupy when the cover 17 is being closed.

The previously described locking means for locking the operating handle 45 in the "off" position also cooperates with the interlocking means 75 for the cover, to lock the cover in closed position. Since the interlocking means 75 is effective to lock the cover 17 when the operating handle is in the "off" position, locking of the operating handle 45 in the "off" position also prevents opening of the cover, thus a single padlock when inserted in the apertures 111 and 117 is effective to lock the operating handle in the "off" position and also the cover in the closed position.

In order to permit opening of the cover 17 by an authorized person without first opening the breaker 27, a lever 129 inside the cover is rigidly secured to screw 131 which is mounted in the cover 17. The free end of the lever 129 is adapted to engage and move the locking element 79 to released position when the screw 131 is turned in a clockwise direction. The screw 131 is mounted on the cover 17 in a position such that it is covered by the operating handle 45 when the handle is in the "off" position. When the operating handle is in the "on" position, the screw is exposed and an authorized person may

turn the screw, by means of a screwdriver or the like, to effect release of the cover locking means, so that the cover may be swung to open position without opening the breaker.

The cover 17 instead of being hinged to the casing 15 may be removably mounted thereon in any suitable manner, as for example, by providing the cover and casing with flanged edges and bolting the flanges together. In this case, suitable dowel pins would be provided on the flange of the casing to engage opening provided therefor in the cover flange to prevent shifting of the cover and opening of the cover except when the interlock 15 is released.

From the foregoing description, it will be seen that the invention provides a circuit breaker or switch enclosing cabinet having an improved operating device for operating the breaker within the cabinet. The operating device automatically causes the operating handle on the cover to assume a position corresponding to that of the breaker handle and effects an operative connection between the handles when the cover is closed, even though the handles may be in non-corresponding positions when the cover is closed. The construction of the operating device is also such that it prevents breakage of the breaker handle when the cover is slammed shut. The invention also provides an improved interlock for locking the cover of the cabinet closed in all positions of the operating handle except when the handle is moved to "open cover" position beyond the "off" position, thus insuring that the breaker is open before the cover may be opened. The interlock also serves to prevent accidental movement of the breaker handle to the "on" position when the cover of the cabinet is open.

While the invention has been disclosed in accordance with the provisions of the patent statutes, it is to be understood that various changes in the structural details thereof may be made without departing from the spirit of the invention. It is desired, therefore, that the appended claims be given the broadest reasonable construction permissible in the light of the prior art.

I claim as my invention:

1. In combination with a circuit interrupter unit having a movable handle of insulating material, a casing in which the interrupter unit is mounted, an openable cover for said casing, an operating member movably mounted in said casing and having means for engaging and moving said interrupter handle, an operating handle mounted on said cover for movement in only a single plane for moving said interrupter handle to operate the interrupter, and means operable to effect an operative connection between said handles when the cover is closed, said means preventing breaking of said interrupter handle when the cover is slammed shut.

2. In combination with a circuit interrupter unit having a movable handle of insulating material, a casing in which the interrupter unit is mounted, an openable cover for said casing, an operating member movably mounted on a fixed support in said casing and having means for engaging and moving said interrupter handle, an operating handle on said cover having means which is disposed in the path of movement of said operating member at all times when the cover is closed and which is engageable with said operating member for moving said operating

member to various positions to actuate the interrupter by means of said operating handle.

3. In an enclosing cabinet for a circuit interrupter unit having a movable handle of insulating material, a casing in which the unit is mounted, an openable cover for said casing, an operating member movably mounted in said casing having means for engaging and moving said interrupter handle, a movable operating handle on said cover having means releasably engaged with said operating member upon closing of said cover for moving said operating member to actuate said interrupter, the mounting of said operating member serving to prevent breakage of said interrupter handle when the cover is slammed shut.

4. In an enclosing cabinet for a circuit interrupter unit having a movable handle of insulating material, a casing in which the interrupter unit is mounted, an openable cover for said casing, an operating member movably mounted on a support in said casing and having resilient means for engaging and moving the interrupter handle, and means including an operating handle on said cover for moving said operating member to actuate the interrupter, said resilient means preventing breakage of said interrupter handle when abnormally large forces are applied to said operating handle, and the mounting of said operating member serving to prevent breakage of said interrupter handle when the cover is slammed shut.

5. In an enclosing cabinet for a circuit interrupter unit having a movable handle, a casing in which the interrupter unit is mounted, an openable cover for said casing, an operating handle mounted on the exterior of said cover having a rotatable shaft extending through said cover and a member connected to the shaft inside said cover, an operating member movably mounted in said casing separably engaged by the member connected to said shaft and having means for engaging and moving the interrupter handle to operate the interrupter by means of the operating handle on the exterior of the cover.

6. In an enclosing cabinet for a circuit interrupter unit having an oscillatable handle, a casing in which the interrupter unit is mounted, an openable cover for said casing, an operating member movably mounted in said casing and having means for engaging and moving the handle of the interrupter, and means including an operating handle rotatably mounted on said cover for movement in a plane perpendicular to the plane of movement of said interrupter handle, said operating handle having means for separably engaging said operating member and being operable to move said operating member to various positions to actuate the interrupter.

7. In an enclosing cabinet for a circuit interrupter unit having an oscillatable handle of insulating material, a casing in which the interrupter unit is mounted, an openable cover for said casing, an operating member movably mounted in said casing and having resilient arms for engaging the opposite sides of the interrupter handle to move said handle, an operating handle rotatably mounted on said cover having a shaft extending through said cover, and a member secured to said shaft inside said cover for releasably engaging and rotating said operating member to various positions to operate the interrupter.

8. In an enclosing cabinet for a circuit inter-

rupter unit having a movable handle of insulating material, a casing in which the interrupter unit is mounted, an openable cover for said casing, a rigid support for mounting in said casing, an operating member movably mounted on said support and having means for engaging and moving the handle of the interrupter, an operating handle movably mounted on the exterior of said cover having means engaged with said operating member upon closing of said cover for moving said operating member to various positions to operate said interrupter, said rigid support and the mounting of said operating member thereon serving to prevent breakage of said interrupter handle when the cover is slammed shut.

9. In combination with a circuit interrupter unit having a movable handle, a cabinet for enclosing said interrupter and having an openable cover, an operating handle on said cover movable to various positions for moving said interrupter handle to corresponding positions to operate the interrupter, and means for automatically causing said operating handle and said interrupter handle to assume corresponding positions and for automatically effecting an operative connection between said handles when the cover is closed even though said handles are in non-corresponding positions during closing of said cover.

10. In an enclosing cabinet for a circuit interrupter unit having a movable handle, a casing in which the interrupter unit is mounted, an openable cover for said casing, an operating handle on said cover movable to an "on" and to an "off" position for moving said interrupter handle to corresponding positions to operate the interrupter, and means for automatically causing said operating handle to assume a position corresponding to that of said interrupter handle and for automatically effecting an operative connection between said handles when the cover is closed even though said handles are in non-corresponding positions during closing of said cover.

11. In an enclosing cabinet for a circuit interrupting unit having a movable handle, a casing in which the interrupter unit is mounted, an openable cover for said casing, an operating handle on said cover movable to an "on" to an "off" and to a "reset" position for moving said interrupter handle to corresponding positions to operate the interrupter, and means for automatically causing said operating handle to assume a position corresponding to that of said interrupter handle and for effecting an operative connection between said handles when the cover is closed irrespective of difference of positions of said handles relative to one another during closing of said cover.

12. In an enclosing cabinet for a circuit interrupter unit having a movable handle, a casing in which the interrupter unit is mounted, an openable cover for said casing, an operating handle on said cover movable to an "on" and to an "off" position for moving said interrupter handle to corresponding positions to operate the interrupter, and means for automatically causing said operating handle to assume a position corresponding to that of said interrupter handle and for effecting an operative connection between said handles when the cover is closed even though said interrupter handle is in one extreme position and the operating handle may

have been moved to the opposite extreme position before the cover is closed.

13. In combination with a circuit interrupter having a movable lever, a cabinet for enclosing said interrupter having an openable cover, means including an operating handle on said cover for moving said interrupter lever to various positions to operate said interrupter, said means including interengaging members one of which is carried by said cover and movable with said operating handle and the other of which is mounted in said cabinet and movable with said breaker lever, said members when interengaged forming an operative connection between said operating handle and said lever, and means for automatically causing said members to interengage when said cover is closed irrespective of difference of positions of said members relative to one another during closing of said cover.

14. In an enclosing cabinet for a circuit interrupter unit having a movable handle, a casing in which the interrupter unit is mounted, an openable cover for said casing, means including an operating handle on said cover for moving the interrupter handle to various positions to operate the interrupter, said means including interengaging members one of which is carried by said cover and movable with said operating handle and the other of which is mounted in said casing and movable with said interrupter handle, said members when interengaged forming an operative connection between said handles, and means for automatically causing said members to operatively interengage when said cover is closed even though said members are in different positions relative to one another during closing of said cover.

15. In an enclosing cabinet for a circuit interrupter having a movable handle, a casing in which the interrupter is mounted, an openable cover for said casing, an operating handle on said cover movable to various positions for moving said interrupter handle to corresponding positions to operate the interrupter, and means for automatically causing said operating handle to assume a position corresponding to that of said interrupter handle and for effecting an operative connection between said handles when the cover is closed irrespective of difference of positions of said handles relative to one another during closing of the cover, said means including a spring for biasing said operating handle to an intermediate position when the cover is open.

16. In an enclosing cabinet for a circuit interrupter having a movable handle, a casing in which the circuit interrupter is mounted, an openable cover for said casing, an operating handle on said cover movable to various positions for moving said interrupter handle to corresponding positions to operate the interrupter, a spring for biasing said operating handle to an intermediate position when the cover is open, and means for causing said operating handle to assume a position corresponding to that of said interrupter handle and for effecting an operative connection between said handles when the cover is closed irrespective of the position said interrupter handle occupies during closing of said cover.

17. In an enclosing cabinet for a circuit interrupter having a movable handle, a casing in which the interrupter is mounted, an openable cover for said casing, an operating member movably mounted on a support in said casing and

having means for engaging and moving said interrupter handle, an operating handle on said cover movable to various positions for moving said operating member and interrupter handle to corresponding positions to operate the interrupter, said operating handle having means for interengaging said operating member when the cover is closed to establish an operative connection between said handles, and means for automatically causing said operating handle to assume a position corresponding to that of said operating member and interrupter handle, and for causing said handle means to interengage said operating member when the cover is closed irrespective of difference of positions of said operating handle and operating member relative to one another during closing of said cover.

18. In combination with a circuit interrupter having a movable handle, a casing in which the interrupter is mounted, an openable cover for said casing having an operating handle thereon movable to an "on" and to an "off" position for moving said interrupter handle to corresponding positions to operate the interrupter, said operating handle also being movable to an "open cover" position different from the "on" and "off" positions, interlocking means enclosed by said casing and cover comprising a movable latch element for normally locking said cover to prevent opening thereof, said operating handle being operable only when moved to said "open cover" position to move said latch element and release said locking means to permit opening of the cover, said movable latch element preventing accidental movement of said interrupter handle to the "on" position when the cover is open.

19. In combination with a circuit interrupter having a movable handle, a casing in which the interrupter is mounted, an openable cover for said casing having an operating handle movable to an "on" to an "off" and to a position beyond the "off" position for moving said interrupter handle to corresponding positions to operate the interrupter, interlocking means enclosed by said casing and cover for normally locking said cover to prevent opening thereof, and means movable by said operating handle for releasing said interlocking means to permit opening of said cover, said means being operable to release said interlocking means only when said operating handle is moved to said position beyond the "off" position, said interlocking means being operable to prevent accidental movement of said interrupter handle to the "on" position when the cover is open, and having provision for receiving a lock to prevent movement of said interrupter handle to the "on" position when the cover is open.

20. In an enclosing cabinet for a circuit interrupter having a movable handle, a casing in which the interrupter is mounted, an openable cover for said casing having an operating handle for moving the interrupter handle to operate the interrupter, said operating handle being movable to an "on" position to an "off" position and to an additional "open cover" position, interlocking means enclosed by said casing and cover comprising a movable latch element for normally locking said cover to prevent opening thereof, said operating handle being operable only when moved to said "open cover" position to move said latch element and release said interlocking means to permit opening of said cover, said movable latch element being operable to prevent accidental movement of said

interrupter handle to "on" position when said cover is open.

21. In combination with a circuit interrupter having a movable handle, a casing in which the interrupter is mounted, an openable cover for said casing, an operating member movably mounted on a support in said casing and having arms for engaging and moving said interrupter handle, an operating handle on said cover movable to an "on" to an "off" and to an "open cover" position beyond the "off" position for moving said operating member and interrupter handle to corresponding position to operate the interrupter, interlocking means enclosed by said casing and cover for normally locking said cover to prevent opening thereof comprising a locking element carried by said cover, a movable locking element mounted on said support and biased to engage said locking element on said cover, said operating handle being operable only when moved to the "open cover" position to cause said operating member to engage and move said movable locking element to released position to permit opening of said cover, said movable locking element being operable to prevent movement of said operating member and interrupter handle to the "on" position when said cover is open.

22. In an enclosing cabinet for a circuit interrupter, a casing in which the interrupter is mounted, said casing having an openable cover, an operating handle on said cabinet movable to an "on" and to an "off" position to actuate the interrupter, interlocking means in said cabinet for normally locking said cover closed when said handle is in "on" and in "off" positions, said handle being operable to release said interlocking means to permit opening of said cover only upon movement of said handle to a position beyond the "off" position, means having provision for receiving a padlock to lock said handle in "off" position, and movable means on said cabinet separate from said interlocking means and operable from outside said cabinet to release said interlocking means when said handle is in "on" position, said movable means being inoperable from outside said cabinet when said handle is in "off" position.

23. In an enclosing cabinet for a circuit interrupter, a casing in which the interrupter is mounted, an openable cover for said casing, an operating handle on said cabinet movable to an "on" and to an "off" position to actuate the interrupter, interlocking means in said cabinet for normally locking said cover to prevent opening thereof, said operating handle being operable only when moved to an "open cover" position beyond the "off" position to effect release of said interlocking means to permit opening of said cover, and a lever operable from outside said cabinet to effect release of said interlocking means to permit opening of the cover when the handle is in the "on" position, said lever being inoperable from outside said cabinet when the handle is in the "off" position.

24. In combination, a casing having an openable cover, a circuit interrupter unit having a movable handle mounted in said casing, an operating handle on said cover for moving said interrupter handle to operate the interrupter, a separable operative connection between said handles, said separable connection being engageable to automatically effect complete operative connection of said handles when the cover is closed irrespective of the position of said interrupter handle.

25. In combination, a casing having an open-

able cover, a circuit interrupter unit having a movable handle mounted in said casing, an operating handle on said cover for moving said interrupter handle to operate the interrupter, a separable operative connection between said handles, said separable connection being engageable to effect complete operative connection between said handles upon movement of the operating handle irrespective of the position of said interrupter handle when the cover is closed.

26. In combination, a casing having an openable cover, a circuit interrupter unit having a movable handle mounted in said casing, an operating handle on said cover for moving said interrupter handle to operate the interrupter, a separable operative connection between said handles, said separable connection being engageable to effect complete and correct operative connection between said handles when the cover is closed irrespective of the difference of positions of the handles at the time the cover is being closed, the operative connection between said handles being completed by the movement of said operating handle to a position corresponding to that of said interrupter handle when the cover is closed with the handles in non-corresponding positions.

27. In combination, a circuit interrupter unit having a movable handle, a casing for enclosing said unit having an openable cover, an operating member movably mounted on a fixed support in said casing and having means for engaging and moving the interrupter handle, an operating

handle on said cover movable to "on" and "off" positions for actuating the interrupter, said operating handle having a projection inside said cover for engaging and moving said operating member, 5 said operating member having a flange with a notch to fit said projection when the cover is closed, the flange having inclined edges leading to said notch for automatically moving said operating handle to a position corresponding to that 10 of said interrupter when the cover is closed, and spring means for biasing said operating handle to a position intermediate the "on" and "off" position when the cover is open.

28. An enclosed switch comprising a box, a cover hinged thereto, circuit making and breaking mechanism in said box, an operating handle on said cover movable to "on" and "off" positions for actuating said mechanism, said handle having a projection inside said cover, an operating member in said box connected to said mechanism, said member having a flange with a notch 15 to fit said projection when the cover is closed, said flange having inclined edges leading to said notch for automatically moving said operating handle to the "on" or "off" position corresponding to the position of said circuit making and breaking mechanism when the cover is closed to connect said operating handle with said mechanism, and spring means for biasing said operating handle to a position intermediate the "on" and "off" positions when the cover is open.

DELBERT ELLIS.
